US00D961989S

(12) **United States Design Patent** (10) Patent No.: **US D961,989 S**
McConnell et al. (45) Date of Patent: **** Aug. 30, 2022**

(54) **FOOD GRINDER**

- (71) Applicant: **WHIRLPOOL CORPORATION**,
Benton Harbor, MI (US)
- (72) Inventors: **John W. McConnell**, St. Joseph, MI
(US); **Nicholas H. Schutte**, St. Joseph,
MI (US); **Brandon T. Mock**, St.
Joseph, MI (US)
- (73) Assignee: **Whirlpool Corporation**, Benton
Harbor, MI (US)

(**) Term: **15 Years**

(21) Appl. No.: **29/816,366**

(22) Filed: **Nov. 22, 2021**

Related U.S. Application Data

(63) Continuation of application No. 29/796,238, filed on
Jun. 23, 2021, now Pat. No. Des. 939,267, which is a

(57) **CLAIM**

The ornamental design for a food grinder, as shown and
described.

DESCRIPTION

FIG. 1 is a top-front perspective view of a food grinder
according to the design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a back-bottom perspective view thereof.

The portions of the article shown in even broken line form
no part of the claimed design.

1 Claim, 8 Drawing Sheets
